Primary Examiner—Stacia Cadmus(74) Attorney, Agent, or Firm—Nixon Peabody LLP;
Donald R. Studebaker(57) **CLAIM**

The ornamental design for a center consol of motor vehicle, as shown and described.

DESCRIPTION

FIG. 1 is a perspective view of a center console of motor vehicle;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Portion in broken lines is shown for illustrative purposes only and forms no part of the claimed design.
